Patented Oct. 7, 1913

UNITED STATES PATENT OFFICE.

ZENAS L. MELICK, OF PUEBLO, COLORADO, AND ED F. DUNN, OF OKLAHOMA,
OKLAHOMA.

HYDROCARBON-OIL BURNER.

1,075,299.

Specification of Letters Patent.

Patented Oct. 7, 1913.

Application filed February 11, 1913. Serial No. 747,763.

To all whom it may concern:

Be it known that we, ZENAS L. MELICK, a citizen of the United States, residing at Pueblo, in the county of Pueblo and State of Colorado, and Ed F. DUNN, a citizen of the United States, residing in the city of Oklahoma, county of Oklahoma, and State of Oklahoma, have invented new and useful Improvements in Hydrocarbon-Oil Burners, 10 of which the following is a specification, reference being had to the accompanying drawing.

This invention relates to hydrocarbon oil burners, and to means for treating the flames 15 therefrom.

It is an object of invention, among others, to provide novel, yet practical and simple means for treating the flames resulting from the burner pipe, whereby to prevent the casting off of obnoxious odors and products.

To reduce the invention to practice suitable forms and arrangements of mechanism may be employed, so long as the essence of invention is maintained, and to one of 25 such arrangements, this specification will refer.

In the drawings, forming a part of the specification, Figure 1 is an elevation view, partly in section, of a stove with the invention applied. Fig. 2 is a plan view of the air-shaft, vaporizer, deflectors, and the drip pan. Fig. 3 is an elevation view of a trough. Fig. 4 is a perspective view of an air-shaft and means associated therewith for treating 35 the flame from the burner pipe.

In said views, similar parts are to be referred to by similar characters of reference.

The drip-pan 5 is provided with one or more air-shafts 6, and the upper ends of 40 these are disposed above the bottom of the drip pan. Suitable closures are provided for said air-shafts 6, and they are shown as hinged closures associated with the bottom of the drip pan and are provided with 45 notches 7 to receive therein the respective turn-buttons 70 attached to the bottom of the drip-pan.

Suitably supported by the casing forming the air shafts 6, and perhaps, preferably in 50 recesses 8, are troughs 9 the opposite ends of which overhang a trough 10, so that the said troughs may not only discharge into the trough 10, but provide a substantially continuous trough, in order that only a small 55 amount of fuel may escape therefrom onto

the drip-pan, and consequently provide for complete consumption of the fuel product. Again, by an arrangement of this character, not only will the device be more cleanly, but less dangerous, inasmuch as drip-pans 60 laden with combustible material render devices of this kind unsafe at unguarded or unsuspecting moments, and, furthermore, by bringing the ignited flame in close proximity with the burner, carbonization of the 65 flame tip is prevented and the full benefit of that flame may be utilized for the purpose of immediate generation. Therefore this will eliminate soot and other objectionable 70 matters and results. In Fig. 1 this substantially continuous trough is constructed by the two troughs 9 overhanging the trough 10, which, for simplicity of construction, may be the form most desirable, especially 75 in case of repair, but in Fig. 3 there is shown a trough made from one piece, comprehending the end troughs 11 and 12, which are connected to a depressed trough 13 through depending ways 14 and 15. This form may be of service in case it is desirable 80 to stamp the trough from one piece. Mounted in these end troughs, either 9 or 11 and 12, is a portion of pipe 16, which is connected to a vaporizer 17 that is suitably associated with the burner pipe. The burner pipe is 85 provided with openings or perforations, (not shown) that are located in the troughs and through which comes the fuel to be burned. Suitable deflectors are provided, and may be suitably associated with the burner pipe, and they comprise plates 18 and 19, that depend 90 from hangers 20 and 21 that are associated with the vaporizer 17. Thus, hanging as they do, above the air shaft, they will spread the flame and distribute the same 95 over a practical and desirable area whereby to obtain the benefits from heating units. The burner pipe and vaporizer are connected, in a suitable way to a feed-pipe 22 that may be connected in any suitable way 100 to a source of supply.

Hydrocarbon oil burners have an objection in that they emit, as a rule, obnoxious products, such, for instance, as soot. The present invention provides for care for this 105 matter. In suitable association with the air shafts 6 there are provided vats to receive water. These vats are designated by 23 and are shown as being attached to the air shafts 6. They may however be made integral 110

with the air shafts. The water in these vats is heated by the flame coming from the burner pipe, and the vapor arising from the heated water is sufficient to treat the flame 5 to prevent the throwing off of the objectionable products. Aside from allowing the troughs 10 or 13 to catch the oil, the said trough may be used to pre-heat the burner pipe by causing the oil caught therein to be 10 ignited under the burner, thereby placing the burner ready to gasify the incoming oil.

Having thus described this invention, we claim.

1. A hydrocarbon oil burner comprising 15 a burner-pipe, air shafts therefor, a trough extending across each shaft, a second trough beneath the first named troughs and into which they empty, a drip pan under the burner pipe and troughs, means to vaporize 20 the fuel, and water vats in proximity of the burner-pipe for treating the flame.
2. A hydrocarbon oil burner comprising a burner pipe, air shafts therefor, a vaporizer, deflectors, a depressed receptacle running beneath the burner pipe, and a drip pan beneath said receptacle.
3. A hydrocarbon oil burner, comprising 25

a burner pipe, air shafts therefor, a vaporizer, deflectors, a depressed receptacle running through the device and under the 30 burner pipe, a drip pan beneath said receptacle, and a vat secured to each air-shaft for holding water to be heated by the flame from the burner-pipe so that said heated water may vaporize the flame.

35 4. A hydrocarbon oil burner comprising a burner-pipe, air shafts therefor, a vaporizer, deflectors, troughs in the air shafts, a trough into which said troughs empty, a drip pan beneath the last mentioned trough, and 40 a vat secured to each air-shaft for holding water to be heated by the flame from the burner pipe so that the heated water may vaporize the flame.

Signed at the city, county and State of 45 Oklahoma this 8th day of February, in the year of our Lord nineteen hundred and thirteen.

ZENAS L. MELICK.
ED F. DUNN.
